UNITED STATES PATENT OFFICE.

HARRY VERNON SEALE, OF EAST MAITLAND, NEW SOUTH WALES, AUSTRALIA, AND
WILTON SHELLSHEAR, OF NAM-TU, BURMA, INDIA, ASSIGNEES TO MINERALS SEPA-
RATION AMERICAN SYNDICATE (1913) LIMITED, OF LONDON, ENGLAND, A CORPORA-
TION OF GREAT BRITAIN.

CONCENTRATION OF ORES.

1,311,920.

Specification of Letters Patent. Patented Aug. 5, 1919.

Application filed May 23, 1917. Serial No. 170,562.

To all whom it may concern:

Be it known that we, HARRY VERNON SEALE and WILTON SHELLSHEAR, subjects of the King of Great Britain, and both formerly residing at Junction North Mine, Broken Hill, in the State of New South Wales, Commonwealth of Australia, but now residing, respectively, at East Maitland, New South Wales, Commonwealth of Australia, and Nam-tu, Northern Shan States, Burma, India, have invented certain new and useful Improvements in Concentration of Ores, of which the following is a specification, reference being had therein to the accompanying drawings, forming part thereof.

This invention relates to apparatus for the concentration of sulfid and other ores by the process generally known as flotation separation, and contains divisional subject-matter disclosed and broadly claimed in our United States Patent application Serial No. 37,350, filed June 30, 1915, and is to that extent a continuation thereof. While relating to flotation separation broadly, the invention is more especially concerned with froth flotation separation in which the ore pulps are aerated, generally with the assistance of a frothing agent, to form a floating froth containing the metalliferous mineral particles.

The apparatus comprising this invention is equally applicable either to collective separation for the recovery of an indiscriminate float concentrate of metalliferous minerals, or for the differential or preferential flotation separation of certain particular metalliferous minerals in discrimination against other metalliferous minerals carried in the pulp. Also the invention is equally applicable to the treatment of ores, concentrates, tailings, slimes or other metallurgical products, and it will be understood that the term "ores" as employed in this specification includes all such metallurgical products as well as crude materials.

Simplicity, economy, efficiency and reliability of construction and operation are the objects of the invention.

The expressions "air" and "aeration" are used in the following claims as understood

in the art and are intended to include other suitable gases and gasification, as indeed air is but a mixture of gases in somewhat varying proportions. The present invention relates particularly to the means of injecting air into the ore pulp.

In the accompanying drawings:

Figure 1 is an elevation of an ore concentrating system embodying our invention; and

Fig. 2 is an enlarged sectional elevation representing the interior of the air-injecting means and separating vessels.

E is a feed box or pulp reservoir, which, by any suitable means, is supplied with an ore pulp maintained at an approximately constant level within the box. The ore pulp continuously flows by gravity from the feed box E through the vertical conduit B¹ and into the first separating vessel A. This gravity flow of pulp induces an eruption of air through the perforations B² in the upper end of this conduit by virtue of an injector arrangement which is duplicated at the upper end of each of the successive conduits B¹, which also convey the pulp by gravity from each separating vessel to the next throughout the entire series, as represented. This air injector at the upper end of each vertical conduit B¹ comprises a nozzle A⁴ which receives the pulp from the vessel above and which is somewhat smaller in diameter than the passageway through the conduit so as to leave an annular air-induction space between the nozzle and the conduit walls, which space communicates with the outer air through perforations B² in the conduit. The rush of pulp from the lower end of the nozzle engages the surrounding air and forces it downward so as to induce a subpressure in the air-induction space and effect a violent eruption of air through the inlets B² which mixes with the pulp in its fall.

The lower end of each conduit discharges the pulp into the next succeeding separation vessel at a point below the liquid level therein, and preferably against a deflecting baffle such as A¹ suitably mounted in the separating vessel and serving to churn the mixed pulp and air into a more perfect

emulsion to produce the desired flotation froth which overflows from the separator into the launder A² carrying with it the desired concentrates which may be drained off in a pipe F. An annular upper baffle such as A³ may be employed to deflect the rising froth toward the overflow edge of the separating vessel.

Thus the course of pulp flow leads 10 through the successive air injectors and separating vessels while each separating vessel subtracts its concentrate by froth flotation and delivers its residue pulp to the separating vessel next in order, so that each vessel 15 acts as a feed box for the next vessel. The loss of liquid thus entailed by the delivery to each launder may be compensated by extra liquid admitted to the successive conduits B¹ through small pipes under control 20 of regulating valves D¹ and taking their supply from the pipe line D connected with a suitable source G. Manifestly the rate of overflow from the successive separating vessels can be governed by the adjustment of 25 these valves controlling the supplemental liquid supply.

The form of the invention may be widely varied within the spirit and scope of the following claims:

- 30 1. Apparatus for the concentration of ores by flotation-separation comprising a froth-separating vessel, a pulp conduit leading into the froth-separating vessel and including an inner jet-discharging nozzle 35 rounded by the outer conduit-wall with an intervening air-induction space surrounding the nozzle, one or more air inlets leading to the air-induction space from the outer air, and means for producing a flow of pulp 40 through the conduit and its nozzle and into the froth-separating vessel, with such velocity that the flow of pulp through the nozzle and conduit will induce irruption of air to aerate the pulp, and the hydraulic 45 violence of pulp flow will effect that degree of agitation necessary for the formation of mineral-carrying froth.
2. Apparatus for the concentration of ores by flotation-separation comprising a froth-separating vessel, a pulp-conduit leading 50 into the froth-separating vessel and including an inner jet-discharging orifice arranged to discharge a jet of pulp into an air-induc-

tion space within the conduit but communicating with the outer air, a baffle disposed 55 in the froth-separating vessel in the path of the pulp flow, and means for producing a flow of pulp through the conduit and into the froth-separating vessel and against the baffle with such velocity that the flow of 60 pulp through the jet orifice and conduit will induce irruption of air to the pulp and the hydraulic violence of the pulp flow against the baffle will effect that degree of agitation necessary for the formation of a mineral- 65 carrying froth.

3. Apparatus for the concentration of ores by flotation-separation comprising a separating vessel having a residues outflow at the bottom, a feed box open at the top, and a 70 discharge pipe connected to the bottom of the feed box and delivering into the said separating vessel below the surface of the liquid therein and provided with holes to allow the admission of air to form a pulp- 75 operated air injector.

4. Apparatus for the concentration of ores by flotation-separation comprising a separating vessel having a residues outflow at the bottom, a feed box open at the top, a discharge pipe connected to the bottom of the feed box and delivering to the said separating vessel below the surface of the liquid 80 therein and provided with holes to allow the admission of air to form a pulp-operated 85 air injector, and a baffle arranged within the said separating vessel in the path of pulp flow.

5. Apparatus for the concentration of ores by flotation-separation comprising a plurality of separating vessels each provided with a residues discharge pipe at the bottom having 90 holes therein to allow the admission of air to form a pulp-operated air injector and each pipe delivering into the next succeeding 95 separating vessel below the surface of the liquid therein.

In testimony whereof we have signed our names to this specification in the presence of two subscribing witnesses.

HARRY VERNON SEALE.
WILTON SHELLSHEAR.
